(57) **CLAIM**

The ornamental design for an anti-sleep apnea apparatus, as shown and described.

DESCRIPTION

FIG. 1 is a perspective view of an anti sleep apnea apparatus according to the new design.

FIG. 2 is a front view of the anti sleep apnea apparatus.

FIG. 3 is a rear view of the anti sleep apnea apparatus.

FIG. 4 is a left side view of the anti sleep apnea apparatus.

FIG. 5 is a right side view of the anti sleep apnea apparatus.

FIG. 6 is a top plan view of the anti sleep apnea apparatus; and,

FIG. 7 is a bottom plan view of the anti sleep apnea apparatus.

In the drawings, the broken lines depict environmental subject matter only and form no part of the claimed design.

1 Claim, 7 Drawing Sheets
